UNITED STATES PATENT OFFICE.

SAMUEL FELDMAN, OF CHELSEA, MASSACHUSETTS.

PLUG FOR RUBBER HEELS.

1,180,803.

Specification of Letters Patent. Patented Dec. 15, 1914.

Application filed May 15, 1914. Serial No. 335,750.

To all whom it may concern:

Be it known that I, SAMUEL FELDMAN, a citizen of the United States, residing at Chelsea, in the county of Suffolk, State of Massachusetts, have invented certain new and useful Improvements in Plugs for Rubber Heels; and I do hereby declare the following to be a full, clear, and exact description of the invention, such as will enable others skilled in the art to which it appertains to make and use the same.

This invention relates to rubber treads such as are used on shoe heels and soles, crutch tips and on other articles of similar nature and particularly to a type of rubber tread which is reinforced to increase its durability and to prevent slipping.

Applicant is aware that many treads have been provided with differently shaped plugs inserted within the tread and consequently makes no claim on the broad idea of his invention.

The type of plugs commonly used is composed usually of fabric which is folded or wound upon itself, the different folds or convolutions being cemented to each other to form a substantially integral whole. In such plugs the severed ends of the fabric form the top and bottom surfaces of the plug. It has been found by practice that this type of plug has serious disadvantages inasmuch as when the plug becomes worn to any appreciable degree the vertically extending threads will be worn away and will allow the horizontally extending threads to become loosened from the plug causing an unsightly appearance. Furthermore this type of plug has an additional disadvantage of being sufficiently open in its structure, especially after use, that mud and other dirt is liable to collect therein.

The object of the present invention is to eliminate these disadvantages and to produce a tread reinforcing plug of such a character that it will be more resilient and durable than the present type of plug, will greatly decrease the liability of slipping and composed of such material that there are no threads present to become loosened.

More specifically the object of this invention is to provide a plug composed of a strip of material wound in spiral form the various convolutions of which are secured together to form a durable mass. The spiral convolutions performing the function of pro-

viding specially efficient means for preventing slipping as each and every single convolution will in itself act for this purpose.

Other objects and advantages such as simplicity, cheapness, durability and the general improvement of the art will be carefully brought out in the following specification and illustrated in the accompanying drawings, in which—

Figure 1 is a bottom plan view of a heel tread having my improved plug embedded therein, Fig. 2 is a cross sectional view thereon, Fig. 3 is a view similar to Fig. 1 showing a modified form of my device, and Fig. 4 is a cross sectional view through Fig. 3.

Referring more particularly to the drawings, the numeral 5 designates an elastic heel tread such as is commonly applied to shoes, boots, or the like. The heel tread 5 is provided with a recess 6 for the reception of my improved plug to be described.

My improved plug embodies the use of leather instead of fabric for the reason that leather does not comprise any threads which might become loose or raveled from wear.

In the formation of my improved plug it is preferable to superpose a sheet of rubber 7 upon a sheet of leather 8 the two being cemented firmly together as by rubber cement or the like. The two cemented sheets should then be rolled so as to form a spiral and sections may be cut therefrom of the desired thickness. These sections are then inserted within the recess 6 in the tread 5 wherein they may be securely and permanently held by vulcanizing the tread and plug.

In Figs. 3 and 4 I have shown a modified form of the device. In this form the rubber sheet 7 is omitted and the sheet of leather 8 is coated upon one side with a good rubber cement after which it is rolled up into a cylindrical shape as in the first form described.

From an inspection of the drawings and study of the description it will be apparent that in view of the fact fabric is not used in the formation of these plugs that regardless of to how great a degree the tread and plug may become worn the plug will always present a clean and clear cut appearance and cannot ravel out or become in any other manner unsightly. It is also to be observed that this plug is very light in weight and has the additional advantage of being incapable of being drawn away bodily from the tread.

Having thus described my invention what I claim is:

1. A tread comprising a rubber body and a wear-resisting plug embedded therein, said plug being composed of a sheet of leather and a sheet of rubber rolled to form a plurality of spiral convolutions, and means for uniting said leather and said rubber and said convolutions. 25
2. A tread comprising a rubber body and a wear resisting plug embedded therein, 10 said plug being composed of a sheet of leather and a sheet of rubber rolled to form a plurality of spiral convolutions, said plug being vulcanized to unite the convolutions.
3. A tread comprising a rubber body and 15 a wear-resisting plug embedded therein, said plug being composed of a sheet of leather rolled upon itself to form a plurality of spiral convolutions, and rubber cement uniting said spiral convolutions.
4. A tread comprising a rubber body and 20

a wear-resisting plug embedded therein, said plug being composed of a sheet of leather and a sheet of rubber rolled to form a plurality of spiral convolutions, and means for uniting said leather and said rubber and said convolutions.

5. A tread comprising a rubber body and a wear-resisting plug embedded therein, said plug being composed of a sheet of leather and a layer of rubber rolled to form a plurality of spiral convolutions, and cement for holding said leather and rubber together, said plug being vulcanized to unite said convolutions. 30

In testimony whereof, I affix my signature, in the presence of two witnesses.

SAMUEL FELDMAN.
